PROJECTILE

Joseph Raymond Jasse, Paris, France, assignor to
 Societe Nouvelle des Etablissements Brandt,
 Paris, France, a French company

Application February 13, 1950, Serial No. 143,867
 In France February 15, 1949

11 Claims. (Cl. 102—49)

1

The present invention relates to projectiles and in particular to those provided with a hollow charge, which are used in particular for piercing the armour plates of tanks and other appliances.

It is known that the hollow charge effect is ill suited to the rapid gyrations which it is customary to impart to projectiles in order to stabilize them on their trajectories.

On the other hand, in certain other projectiles, it may also be advantageous to relieve one or more portions thereof, such as self-guiding devices, lifting surfaces, and the like from the effects of the rotation.

The invention has for its object a gyroscopically stabilized projectile comprising at least one portion, portion which it is advantageous to relieve from the effect of the gyration, mounted loose in the external body of said projectile so as to be free from the rotation of said body, so that said portion practically does not rotate whereas said body is gyroscopically kept on its trajectory by a rapid rotation about its axis.

In the case of a hollow charge projectile, it is naturally the hollow charge which is freely mounted in the body of the projectile.

In the case of a projectile of the self-propelled type and, preferably, of the self-gyrating type, at least one portion of the self-propulsion charge and, contingently, of the self-gyration charge, is also freely mounted in the body of the projectile in order to avoid the detrimental mechanical effects that the centrifugal acceleration might have on the powder.

In the accompanying drawing, which is given solely by way of example:

Fig. 1 is a diagrammatic longitudinal section of a self-propelled, self-gyrating, hollow charge projectile according to the invention;

Fig. 2 is a transverse section along the line 2—2 of Fig. 1;

Fig. 3 is a diagram showing the progress of the combustion of the blocks of propelling powder adjacent to one of the rear supporting bars;

Fig. 4 is a graph which shows, as a function of the time, i. e. of the positions of the projectile along its trajectory, plotted as abscissae, the values of the pressures exerted on the outer body of the projectile;

Figs. 5 and 6 are fragmentary sections showing two modifications of construction of the nozzles for propelling and gyrating the projectile.

According to the embodiment shown in Figs. 1 and 2, the projectile comprises an outer body 1 of cylindrical shape, made of a light metal or

2

alloy such as Duralumin for example. On the inside, said body is divided by a solid transverse web 2 into two compartments: a front one 3 which opens freely at the front end of said body and is intended to accommodate a hollow charge; and a rear one 4 which opens at the rear end of the body.

The hollow charge, housed in the front compartment 3, comprises a frusto-conical outer body 5 extended towards the front by a conical or frusto-conical cap 6. The explosive charge 7 is housed inside the body 5 between said body and a conical or like inner wall 8 which forms with the cap 6 the cavity 9 of the hollow charge.

15 All the members 5, 6, 8 are centred on the same longitudinal axis X—X as the body 4.

The hollow charge is mounted in the body 1 to be free of any rotation of said body. Said charge is adapted to bear axially, from the front towards the rear, against the web 2 by means of an abutment pivot and is centered in the body 1 by means of two ball-bearings.

15 The abutment pivot is formed by two oppositely located bearing blocks 10 and 11 respectively supported by the body 5 of the hollow charge and by the web 2. One of said bearing blocks (10 for example) is domed or pointed and the other (11) is flat. They are made of tungsten carbide or other material of sufficient hardness. 30 Said bearing blocks are brazed in mountings 12 and 13 of mild steel or any other material of sufficient plasticity to protect said blocks from the shocks which may occur during the handling.

The front guide bearing is formed by balls 14 which are housed: in the axial direction, between two flat bearing surfaces, a rear one 15 provided on a rib 16 of the body 1, and a front one 17 provided on a rib of the casing 5 of the hollow charge; in the radial direction, between 40 a cylindrical surface 18 of said casing 5 and a concentric cylindrical surface 19 of the body 1.

The rear guide bearing is formed in a similar manner; it comprises balls 20 housed in a cup 21 of the web 2 and a recess 23 provided at the rear of the casing 5 of the hollow charge.

As will be understood, owing to the free mounting of the hollow charge in the body 1, when said body is rotated about its longitudinal axis X—X as soon as the shot is fired, whether 50 it is provided with a rifling band and is fired in a rifled gun, or whether its gyration is produced, as will be described hereinafter, by a self-propulsive charge housed in the rear compartment 4, said hollow charge tends by inertia not to move. 55 In fact, the two ball-bearings which guide it tend, by the combined action of the sliding, the

tangential acceleration, the longitudinal acceleration followed by deceleration, and the centrifugal force, to drive the hollow charge in the opposite direction to the body 1, since for each ball-bearing, and for example for the front ball-bearing, by the action of the violent longitudinal acceleration which occurs as soon as the shot is fired, the balls 14 are heavily pressed against the rear bearing surface 15, thereby making it impossible for any sliding of said balls to occur relatively to said bearing surface. The balls then effect a rolling movement on said bearing surface 15, and rotate, on the one hand about themselves about a diameter at right angles to the axis X—X, and on the other hand about said axis. This latter rotation gradually produces on the balls a considerable centrifugal force which presses them heavily against the outer race 19 and prevents any sliding of said balls relatively to said race. The balls then effect a further rolling movement which results in said balls rotating about the axis X—X and about their diameter which is inclined at 45° to said axis X—X. Owing to this rotation of the balls about said diameter, the balls acquire, at their point of contact with the front bearing surface 17 and with the inner race 18, a speed with respect to said surface which is in the opposite direction to their speed with respect to the rear surface 15 and the outer surface 19. The sliding friction between the balls and the surface 18 and, later (at the instant of the deceleration), the front bearing surface 17, tends to eliminate this relative speed between the balls 14 and said bearing surfaces 17 and 18 and consequently to drive the hollow charge in the opposite direction to the body 1.

It is therefore possible, by suitably choosing the diameter of the balls 14 and 20, to arrange for this tendency of the hollow charge to rotate in the opposite direction to the body 1 to compensate almost exactly the tendency to direct rotation due to the friction of the ball-bearing and that of the abutment pivot (10, 11).

By way of example, for a hollow charge weighing about 1.5 kg. and for a projectile of a calibre of about 120 mm., the speed of gyration of which is about 400 revolutions per second, the desired result, i. e. a practically complete immobilization of the hollow charge, is obtained by using a ball-diameter of about 10 mm.

As hereinbefore stated, the gyration of the body 1 may be obtained: either by firing said body in a rifled gun, the body 1 being in this case provided with a usual rifling band and it being possible for the rear compartment to contain another explosive, incendiary, smoke-producing, or like charge, or merely a self-propulsive charge with or without gyroscopic action, or guiding devices, or the like; or by using the ejection through suitably inclined nozzles of pressure gases produced by the combustion of a charge of powder contained in the rear compartment, said charge automatically producing both the propulsion and the gyration.

This latter solution is the one which has been illustrated and which will now be described.

It should first be noted that, owing to the fact that the stabilization of the projectile is obtained by means of the rotation of only a portion of the projectile, and that hollow charge projectiles have their centre of gravity located very much to the rear, it is necessary to impart to the projectile a speed of gyration two to three times greater than in the usual projectiles.

The rear compartment of the projectile there-

fore contains the self-propulsion and self-gyration charge. This charge is formed by a number of concentric coaxial cylindrical cakes of powder 24, 25, 26, 27 (Figs. 1 to 3). The peripheral cylinder 24 is directly housed in the body 1 of the projectile, between a front shoulder 28 of said body and a rear nozzle-supporting member 29 screwed at 30 in the tapped rear end of said body. Said cylinder 24 of powder is slit at 31 (Fig. 2) along its entire length, so as to enable it to follow exactly the deformations of said body for the reasons which will be analysed hereinafter and also in order to facilitate its insertion.

Preferably, between the cake 24 and the body 1 is interposed a coat 32 of a varnish, for example a thermoplastic resin, which adheres perfectly both to the metal and the powder, while allowing for small deformations which are different for the metal and for the powder.

As regards the other cakes 25, 26, 27, which are coaxial with the axis X—X, they are mounted in the projectile so as to be free from the rotation of body 1, since they are held between: on the one hand a star-shaped front grating 33, for example with three arms, provided with projections 34 between which said cakes are engaged; and on the other hand a rear grating comprising radial bars 35 provided on their front face with projections 36 for separating the cakes.

The front grating 33 is adapted to bear, by means of a ball 37, against the bottom of a cup 38 provided in the rear wall of the web 2 of the body 1. Said cup is surrounded by a cylindrical baffle 38a which is supported by the grating and is stuffed with grease.

As regards the rear grating 35 it is supported, by means of a ball 39 housed in a cavity 40 provided at the centre of said grating, by an intermediate element 41 which in turn bears against an adjusting screw 42 screwed in a tapped hole 43 provided at the centre of the rear member 29 that supports the ejection nozzles for the propulsion gases produced by the combustion of the cakes of powder 24 to 27. A cylindrical baffle 43a which is carried by the member 29 and is filled with grease surrounds the cavity 40.

As regards the cakes 25 and 26, on their mutually facing surfaces, small portions of said surfaces adjacent to the points of contact with the corresponding projections 36 of the bars 35 are covered with an insulating material 44 (Fig. 3) which may be of the same nature as that of the aforesaid varnish 32 and which prevents ignition, so that the cakes burn in the manner shown by the dotted lines in Fig. 3.

The propulsion and the gyration are effected by means of a series of peripheral nozzles 45 which are merely fitted into holes provided with a shoulder 46 in the member 29; said nozzles are held in position merely by the thrust exerted on them, from the front towards the rear, by the aforesaid gases. The longitudinal axes Y—Y of said nozzles 45 are inclined with respect to the plane of Fig. 1 in such a manner that the gases which issue from the nozzles cause the body 1 to rotate about its longitudinal axis X—X. The inclination may for example be between 15 and 20° for a distance between the axes Y—Y and X—X of about 35 mm. for a projectile of a calibre of 120 mm.

There is furthermore provided an additional axial nozzle 47 which is normally closed by a disc 48, for example of copper or aluminium, which is intended to blow out if, for any reason, and in particular in the event of the temperature of the block of powder at the instant when the

shot is fired exceeding for example 25° C., the pressure of the gases inside the compartment 4 exceeds a given maximum value that corresponds to the pressure for which the strength of the body has been calculated (for example 150 to 200 kg. per sq. cm.).

Behind the disc 48 is located a safety spider 49 intended to prevent the complete ejection of said disc which might injure the firing attendants if said disc, acting as a veritable projectile, were ejected at the instant when the shot is fired.

Finally, for firing the shot, an electric primer 60 (Fig. 1) is provided which is embedded in a flat pellet 61, charged with superfine black powder. This firing device is preferably housed in the bottom of the compartment 4, against the web 2, the electric conductors for firing, not shown, being located for example between two of the cakes of powder and leading out at the rear through one of the nozzles.

The projectile operates as follows:

When the shot is fired, which is effected by the primer 60, the charge (24, 25, 26, 27) is ignited by the pellet 61.

It should be noted that, owing to the pivotal mounting of all the powder in the body 1, with the exception of the outer cake 24, the cakes 25, 26, 27 only participate slightly in the gyratory movement, so that these cakes are to a great extent shielded from the centrifugal and tangential accelerations.

During the combustion of the powder, the balls 37 and 39 that form pivots are protected from the flames by means of grease that fills the baffles 38^a and 43^a.

It should be noted, on the other hand, that the cake 24, owing to the fact that it only burns with its inner surface 50, protects the body 1 from a rise of temperature and moreover facilitates the lighting of the powder by preventing a powder surface to be lighted being placed opposite the cold wall of the metal body.

The gases produced by the combustion of the powder are ejected through the nozzles 45 and simultaneously effect the propulsion of the projectile and the gyration of the body 1 about the axis X—X without the gyration of the hollow charge for the reasons hereinbefore explained.

If, at any instant, the pressure in the compartment 4 tends to exceed the chosen maximum value, for example 170 kg. per sq. cm., the disc 48 is driven towards the rear (it remains held by the spider 49 so that there is no danger of its injuring the firing attendants) and the central nozzle 47 adds its propulsive action to that of the peripheral nozzles 45. This arrangement enables the highest efficiency of the jet device and therefore the maximum range to be obtained for the most usual temperature conditions, for example 28° C., since above that temperature, through the opening of the central nozzle, the internal pressure falls below the optimum value.

Owing to the very high speed of gyration required for a hollow charge projectile, as hereinbefore explained, this high speed produces a considerable centrifugal force. This centrifugal force increases throughout the duration of the combustion of the charge of powder (i. e. 1 to 2 tenths of a second) and as the projectile moves along its trajectory. Said centrifugal force acts on the body 1 as a radial pressure p^1 .

Consequently, if it is desired, in order to obtain the highest specific efficiency of the jet, to subject the metal throughout the entire duration

of the combustion to a stress approaching its elastic limit, it is necessary to arrange for the total pressure P (Fig. 1), due to the combined action of the aforesaid pressure p^1 and the pressure p^2 due to the gases exerted in the compartment 4, to be kept constant; for this purpose the pressure p^2 must vary in the opposite direction to the pressure p^1 .

This result can be obtained for example: either by the combined use of a highly exothermic powder and nozzles capable of undergoing a rapid and controlled erosion by the action of the gases; thus, it is possible to use ballistite as the powder and make the nozzles of a low-carbon steel, for example about 1 per cent, or, as known, by suitably choosing the shape of the cakes of powder, so as to provide a combustion surface such that it decreases as a function of the time.

Fig. 4 shows, in order to give a more definite idea, the variations of p^1 (curve A), of p^2 (curve B) and of $P=p^1+p^2$ (curve C) as a function of the time t or, what amounts to the same thing, the positions of the projectile along its trajectory. The abscissa t^1 correspond to the end of the combustion of the propulsive charge.

Figs. 5 and 6 show modifications in the manner of constructing the nozzles 51, which are directly formed in the member fixed to the end of the body 1.

In the example of Fig. 5, said member 52 is merely adapted to bear by means of a shoulder 53 against the inner face of an inwardly projecting flange 54 provided at the rear end of the body 1, whereas in the example of Fig. 6, the member 55 is screwed at 56, as in the example of Fig. 1, in the tapped end of the body 1.

Naturally, the invention is in no way restricted to the embodiments illustrated and described, which have only been chosen by way of example.

The non-rotary hollow charge is only taken by way of example of an embodiment and may be replaced by any other device that has to be shielded from the action of the centrifugal force, such as a self-guiding device, lifting surfaces, or the like.

Optionally, the casing 5 of the hollow charge could be provided with projections which would make it possible, by firing the projectile from a rifled tube, to impart to said charge an initial rotation in the opposite direction to that of the body 1 so that, when the impact occurs, the rotation of the hollow charge is substantially eliminated by the frictional forces which tend to rotate it in the direction of said body 1.

Of course, the cakes of powder could be fixed inside the jet device and not freely mounted as shown.

Having now described my invention what I claim as new and desire to secure by Letters Patent is:

1. In a gyroscopically stabilized projectile, an outer body of revolution about a longitudinal axis, said body being provided with at least one cavity which is open at the front of said body and with a transverse partition which terminates said cavity at the rear thereof, a hollow charge housed in said cavity and formed by a hollow container of generally bi-conical shape coaxial to said body, by a substantially conical wall housed in said container in such a manner that its apex is turned towards the rear of said container in which it forms a front chamber and a rear chamber with a concave front face, and by an explosive charge located in said rear chamber,

pivoting means coaxial to said axis and interposed between said container and said transverse partition, a first ball bearing mounted between the lateral wall of said cavity and said container in the region of its largest cross-section, and a second ball bearing between said wall and said container near said pivoting means.

2. A gyroscopically stabilized self-propelled projectile comprising in combination: an outer body which is a body of revolution about a longitudinal axis and which is provided with a front cavity and a rear cavity separated by a transverse partition, an explosive charge of powder which is placed in said front cavity, a transverse support fixed to said body in the rear end of said rear cavity, a set of nozzles carried by said support and through which said rear cavity opens into the atmosphere, a charge of self-propulsion powder housed in said rear cavity for producing propulsion gases which are ejected through said nozzles, at least one portion of said charge being mounted freely in said rear cavity about said longitudinal axis and being free from the rotation of said body, a front grating with radial bars which is arranged parallel to said transverse partition and against which said freely mounted portion of the propulsion charge is adapted to bear from the rear towards the front, a front pivot between said transverse partition and said front grating, a rear grating with radial bars against which the rear end of said freely mounted portion of the self-propulsion charge is adapted to bear from the front towards the rear, and a central pivot device interposed between said rear grating and said nozzle support.

3. Projectile according to claim 2, wherein said central pivot device for pivoting the rear grating on the nozzle support comprises a ball engaged in a central cavity of said grating, a screw screwed in an axial central hole of said support and an intermediate element between said ball and screw, whereby an axial adjustment of the rotary portion of said self-propulsion charge can be effected.

4. Projectile according to claim 2, wherein baffles filled with grease are arranged respectively about said front pivot and said rear pivot device for the respective pivoting of the front and rear gratings in order to protect said front pivot and said pivot device from the action of the combustion gases of said self-propulsion charge.

5. Projectile according to claim 2, wherein means are provided for rendering the strain on said body, due to the centrifugal force and the pressure of the propulsion gases inside said body, substantially constant throughout the entire duration of combustion of said self-propulsion charge.

6. Projectile according to claim 5, wherein said means comprise the combination of a highly exothermic powder that forms said self-propulsion charge, with nozzles which are made of a material capable of undergoing corrosion by the action of the propulsion gases.

7. Projectile according to claim 2, wherein said self-propulsion charge is formed by balistite which is a highly exothermic powder, and said nozzles are made of steel capable of corrosion that contains about 1% of carbon, whereby, owing to the heat of the propulsion gases, the nozzles corrode and produce a drop in the pressure exerted by said gases on the wall of said body, which is substantially the reverse of the variation

of the action of the centrifugal force on said body, in such a manner that said body is subjected to a substantially constant strain by the combined action of said centrifugal force and said pressure due to said gases.

8. Projectile according to claim 2, further comprising, for attenuating the variations of efficiency due to the temperature, a central nozzle located axially in said support, a disc placed in said support behind said central nozzle for normally closing same, said disc being adapted to be driven out automatically if the pressure in said body exceeds a predetermined value, and behind said disc a grating for retaining same and preventing it being converted into a projectile.

9. A gyroscopically stabilized self-propelled projectile comprising in combination: an outer body which is a body of revolution about a longitudinal axis and which is provided with a front cavity and a rear cavity separated by a transverse partition, a hollow charge housed in said front cavity and formed by a hollow container of generally bi-conical shape coaxial to said body, by a substantially conical wall housed in said container in such a manner that its apex is turned towards the rear of said container in which it forms a front chamber and a rear chamber with a concave front face and by an explosive charge placed in said rear chamber, pivot means coaxial to said axis and interposed between said container and said transverse partition, a first ball bearing mounted between the lateral wall of said front cavity and said container in the region of its largest cross-section, and a second ball bearing between said wall and said container near the pivot means, a transverse support fixed to said body in the rear end of said rear cavity, a set of nozzles carried by said support and through which said rear cavity opens into the atmosphere, a charge of self-propulsion powder housed in said rear cavity for producing propulsion gases which are ejected through said nozzles, at least one portion of said charge being mounted freely in said rear cavity about said longitudinal axis and being free of the rotation of said body, a front grating with radial bars which is arranged parallel to said transverse partition and against which said freely mounted portion of the propulsion charge is adapted to bear from the rear towards the front, a front pivot between said transverse partition and said front grating, a rear grating with radial bars against which the rear end of said loosely mounted portion of the self-propulsion charge is adapted to bear from the front towards the rear, and a central pivot device interposed between said rear grating and said nozzle support.

10. In a gyroscopically stabilized projectile, an outer body of revolution about a longitudinal axis, said body being provided with a front cavity, a hollow charge mounted in said cavity to be free of the rotation of said body, said hollow charge being formed by a hollow container of generally bi-conical shape coaxial to said body, by a substantially conical wall housed in said container in such a manner that its apex is turned towards the rear of said container in which it forms a front chamber and a rear chamber with a concave front face and by an explosive charge located in said rear chamber, a thrust and centering device of very small diameter carried by the rear of said container and adapted to bear against the rear bottom of said cavity, and guiding means interposed between the lateral wall of said cavity and said container to center the latter.

11. In a gyroscopically stabilized self-propelled projectile, an outer body of revolution about a longitudinal axis, a self-propulsion charge in said body, said self-propulsion charge comprising a peripheral cylindrical cake of powder which is on the one hand externally coated with an inhibiting substance and on the other hand slit longitudinally so as to be pressed resiliently against the inner face of said body.
